UNITED STATES PATENT OFFICE.

MICHAEL LIPTAK, OF MINNEAPOLIS, MINNESOTA.

FIRE-TILE DOORFRAME.

Application filed April 10, 1924. Serial No. 705,533.

My invention relates to masonry walls, and more particularly to furnace walls, and provides an important improvement in the masonry door frames thereof. Generally stated, the invention consists of the novel construction, combinations and arrangements of parts hereinafter described and defined in the claims.

The so-called "door frame" might be designated as a window frame, because it includes not only the door jambs and arch or transverse upper portion, but also a sill-forming member. However, it is herein designated as a door frame because it will usually be employed as the framework of an opening normally closed by a hinged door. It has hitherto been the general practice to construct these masonry door frames of commercial brick, either common brick, fire brick, or both, and the work incident to laying them up has been very considerable and the expense, consequently, has been quite great.

My invention provides a tile door frame made up of specially constructed tile, preferably fire tile, having such relation to each other that they may be very quickly laid and when laid will produce not only a highly efficient but a very neat or even ornamental-appearing door frame. Moreover, the structure is such that, in a furnace wall, the inner tiles, which are subject to the greatest heat and, hence, more quickly damaged or destroyed than the outer tiles, may be very quickly and easily and at small expense renewed from time to time without requiring the removal of the good or undamaged tile.

In the accompanying drawings, wherein like characters indicate like parts throughout the several views, I have illustrated my invention especially designed for application in a furnace wall to afford what is generally known as an "inspection" door; but it will, of course, be understood that the invention may be more generally applied and employed.

Referring to the drawings:

Fig. 1 is an elevation showing a portion of a furnace wall and a completed fire tile door frame designed in accordance with my invention, looking at the same from the inner side of the furnace;

Fig. 2 is a perspective showing the door frame with some of the tile removed to better illustrate the actual construction;

Figure 3 is a horizontal section taken ap-

proximately on the line 3—3 of Fig. 1; and Fig. 4 is a vertical section taken approximately on the line 4—4 of Fig. 1.

The furnace wall shown is made up of outer bricks 5 and inner bricks 6, the former being common brick and the latter being fire brick. The door frame comprises a shell, door jambs and an arch, each of which is made up of a plurality of tiles, and which members bear an important relation to each other, as will presently appear.

The sill is made up of outer tiles 7 and 8 and inner tiles 7^a and 8^a; the door jambs are made up of outer tiles 9 and inner tiles 9^a; and the arch is made up of outer tiles 11, 12 and 13 and inner tiles 11^a, 12^a and 13^a. Here it is important to note that the inside surfaces, towit: the surfaces of all of the said frame-forming blocks, are beveled toward the interior of the furnace, so that the door opening flares inwardly and, hence, has larger size at the inner surface of the wall than at the outer surface of the wall. This is important because it permits a person at the exterior of the wall, looking through the door opening, to look obliquely upward, obliquely downward and obliquely at both sides and, hence, to inspect a much greater area of the interior of the furnace than would be possible through a door opening having the constant size of the door opening at the outer side of the wall.

The end or terminal sill blocks 8 and 8^a are approximately L-shaped in cross section, but the interior L surfaces thereof are beveled so that the cross sections decrease in a direction from the outer toward the inner surface of the complete wall. The intermediate sill blocks 7 and 7^a are rectangular in cross section. It is, however, important to note that the sill blocks 8^a, at the outer sides of the door frame, are offset so that they break joints with the outer surfaces of the sill blocks 8, as best shown in Fig. 2. It should also be noted that all of the sill blocks 7^a and 8^a, at the bottom of the frame, are set below the sill blocks 7 and 8, as best shown in Fig. 4. The door-jamb-forming blocks 9 and 9^a are tapered so that the door opening flares inwardly, as above stated, and it should be noted that the tiles 9^a, at the outer sides of the frame, are offset from and project beyond the tiles 9, so as to form staggered or broken joints in respect to each other in horizontal planes. Moreover, it should be noted that the tiles 9^a project out-

wardly beyond the tiles 8^a and that the tiles 9 project outwardly beyond the tiles 8.

The arch portion of the door frame is built up on the door jamb made up of the tiles 9 and 9^a. The abutments or terminal blocks 11 and 11^a, usually designated as "skewbacks", are seated, respectively, on the upper tiles 9 and 9^a and project outward beyond the said respective blocks, as best shown in Figs. 1 and 2. The arched tiles 12^a and 13^a are wedge-shaped or tapered, so as to form the desired arch. The central or key tiles 13 and 13^a are, in this preferred arrangement, provided on opposite sides 15 with offset shoulders 14 that widen the upper portions of said blocks.

The arch blocks 12 and 12^a are provided on one side with inset and on the other side with offset shoulders, (see Figs. 1 and 2), 20 that cause them to form lapped joints with the shoulders 14 and with the inner oblique portions of the skewbacks or arch abutments 11. Moreover, the arch blocks 12^a and 13^a are raised higher than the blocks 12 and 13 25 and at their extremities are provided with projecting ends 12' and 13', (see Figs. 2 and 4), that overlap the inner extremities of the blocks 12 and 13, respectively. These overlapping joints very securely support the 30 blocks 12^a and 13^a and prevent said blocks from settling in the arch.

By reference particularly to Figs. 1 and 2, it will be noted that, by projecting the jamb-forming blocks 9 and 9^a beyond the 35 blocks 8 and 8^a, the said projecting portions are caused to rest upon certain of the bricks of the masonry 6, thereby supporting the door jambs independently of the sill structure. Also, by likewise projecting the skew- 40 backs or abutment blocks 11 and 11^a beyond the blocks 9 and 9^a, said blocks 11 and 11^a are rested in part upon certain of the bricks of the masonry 6 and are thereby supported independently of the door jambs. 45 This permits the sill blocks to be removed and replaced while the jamb-forming blocks are in position and permits the jamb-forming blocks to be removed and replaced while the complete arch is in position.

50 The various blocks that form this tile door frame may be cheaply made and, as is evident, may be laid up very rapidly. Of course, the inner blocks 7^a, 8^a, 9^a, 11^a, 12^a and 13^a will be subjected to much greater heat 55 than the corresponding outer blocks 7, 8, 9, 11, 12 and 13, and all or any of the said inner blocks may be readily replaced when burned away, without disturbing the said outer blocks. Also, more or less of the fire 60 bricks 6 of the main body of the wall may be replaced, but this does not constitute part of the present invention.

Not only may this improved fire tile door frame or doorway lining be installed at less 65 cost than the ordinary fire brick structures,

but it has a better appearance and is more efficient, and, of course, from what has been said, it follows that it may be more readily repaired at lower cost than the ordinary fire brick structure.

70

Any suitable form of door may be used in connection with this masonry door frame, but I have shown an ordinary cast metal door 14 hinged at 15 to a cast rectangular frame 16 suitably secured to the outer face 75 of said door frame.

What I claim is:

1. A door frame, comprising supplemental inner and outer jamb-forming blocks, and supplemental inner and outer arch-forming blocks, said inner arch-forming blocks having 80 terminal extensions resting and slidable upon the outer arch-forming blocks.

2. A door frame, comprising supplemental inner and outer jamb-forming blocks, and supplemental inner and outer arch-forming blocks, said arch-forming blocks having terminal blocks that project laterally beyond the upper jamb-forming blocks, and the inner arch-forming blocks having terminal extensions which rest and may slide upon the outer arch-forming blocks.

3. A tile door frame made up of sill-forming blocks, jamb-forming blocks and arch-forming blocks constructed and arranged to fit together to form a complete frame, said jamb-forming blocks projecting laterally beyond the sill and the terminal blocks of the arch projecting laterally beyond said jamb-forming blocks.

4. In a masonry wall, a tile door frame made up of supplemental inner and outer sill-forming blocks, supplemental inner and outer jamb-forming blocks, and supplemental inner and outer arch-forming blocks constructed and arranged to fit together to form a complete frame, said jamb-forming blocks projecting laterally into the wall beyond said sill-forming blocks, and the terminal blocks of said arch projecting laterally into the wall beyond said jamb-forming blocks.

5. In a masonry wall, a tile door frame made up of supplemental inner and outer sill-forming blocks, supplemental inner and outer jamb-forming blocks, and supplemental inner and outer arch-forming blocks constructed and arranged to fit together to form a complete frame, said jamb-forming blocks projecting laterally into the wall beyond said sill-forming blocks, and the terminal blocks of said arch projecting laterally into the wall beyond said jamb-forming blocks, the exposed inner surfaces of said blocks being beveled toward the inner face of the wall so that the door opening is given an inward flare.

6. In a masonry wall, a tile door frame made up of supplemental inner and outer sill-forming blocks, supplemental inner and outer jamb-forming blocks, and supplemental

120

115

120

125

130

tal inner and outer arch-forming blocks constructed and arranged to fit together to form a complete frame, the inner arch-forming blocks overlapping adjacent ends of the corresponding outer arch-forming blocks and extending vertically about the same.

7. In a masonry wall, a tile door frame made up of supplemental inner and outer sill-forming blocks, supplemental inner and outer jamb-forming blocks, and supplemental inner and outer arch-forming blocks constructed and arranged to fit together to form a complete frame, and which terminal sill-forming blocks are approximately L-
10 shape in cross section.

8. In a masonry wall, a tile door frame made up of supplemental inner and outer sill-forming blocks, supplemental inner and outer jamb-forming blocks, and supplemental inner and outer arch-forming blocks constructed and arranged to fit together to form a complete frame, and which terminal sill-forming blocks are approximately L-shaped in cross section, the exposed inner surfaces of said blocks being beveled toward the inner face of said wall so that the door opening is given an inward flare.

In testimony whereof I affix my signature.

MICHAEL LIPTAK.
